UNITED STATES PATENT OFFICE.

WILLIAM R. FOX AND HOWARD D. CORWIN, OF JACKSON, MICHIGAN, ASSIGNEES TO
FOX MACHINE COMPANY, OF JACKSON, MICHIGAN, A CORPORATION.

DRILLING MACHINE (MULTIPLE DRILL).

Application filed August 8, 1921. Serial No. 490,662.

To all whom it may concern:

Be it known that we, WILLIAM R. FOX and HOWARD D. CORWIN, citizens of the United States, and residents of Jackson, in the county of Jackson and State of Michigan, have invented certain new and useful Improvements in Drilling Machines (Multiple Drills), of which the following is a specification.

10 The invention relates to multiple drilling machines and consists in the features and combination and arrangement of parts hereinafter described and particularly pointed out in the claims.

15 Our invention is illustrated in the accompanying drawings, in which:—

Figure 1 is a side view of a drilling machine embodying our invention;

Fig. 2 is a front view;

20 Fig. 3 is a side view of the upper end of the column and gear case;

Fig. 4 is a vertical transverse sectional view of the upper gear box containing the change speed gearing;

25 Fig. 5 is a longitudinal section of the upper gear box and gearing;

Fig. 6 is a plan view in the nature of a diagram or a development of the change feed gear of Figs. 4 and 5;

30 Fig. 7 is a vertical cross sectional view of a floating coupling;

Fig. 8 is a sectional plan view partly along the shaft of the shrouded pinion and partly along the clutch shaft;

35 Fig. 9 is a side view of parts of Fig. 8;

Fig. 10 is an end view of parts of Fig. 8;

Fig. 11 is a view of the saddle and a part of the column, and the clutch and gearing for operating the saddle;

40 Figs. 12, 13, 14 and 15 are views of the saddle;

Fig. 16 is a central vertical sectional view of the gear chest of the drill carrying head, for a single speed spindle machine;

45 Fig. 17 is a similar view of a gear chest of a double speed spindle machine;

Fig. 18 is a plan view of a detail.

Fig. 19 shows the head and saddle in section.

50 Fig. 20 is a detail.

The main supporting column is shown at B, having a rack B' fixed by screws and dowels thereto, which rack is engaged by a

pinion C², the teeth of which are cut in a shaft c³ in such manner that the pinion is shrouded. That is to say, the toothed part of the pinion is of no greater diameter than the portions of the shaft at each side of the teeth of the pinion. This shaft bears in saddle C⁵ which is vertically adjustable on the column B by turning the shaft and causing the pinion to roll along the rack. The saddle is held to the column B so as to slide vertically thereon, by gib C⁴, which are screwed to the saddle and bear on the rear faces of the flanges b³ of the slideway of the column. The saddle is recessed on its rear face to receive the slideway portion of the column which acts as a guide therefor. The pinion shaft c³, with its integral shrouded pinion, is assembled with the saddle by simply thrusting it into place longitudinally, and the saddle is then placed into position against the front of the slideway portion of the column. This saddle forms the carrier or support for the head C, in which the drill spindles c' are located, the said head also having a chest C' in which the gears for transmitting motion to the drill spindles are located. The head C and the saddle C⁵ are formed separately from each other, and are bolted together. This two-part construction is of advantage, because it is much cheaper to plane off the saddle, because a number of them can be placed on the planer at the same time; the two parts can be handled more readily than if they were in one piece, and in finishing and fitting the parts together and fitting the saddle to the column, the work is facilitated by this two-part construction. Furthermore, by making the saddle separate from the head C, C', it can be made longer and extended below the lower portion of the head, thus giving more bearing on the column, and, consequently, more firmness to the head. This lengthened construction of the saddle in respect to the head would not be feasible if the two parts were made in one casting, because the head could not then be as readily machined on its lower face and this machining is necessary in order to receive the spindle brackets with accuracy.

A better casting can be made by having the saddle separate from the head. Further, it is possible to mount feed works or a motor

on a portion of the saddle if made separate from the head instead of being made as a part of the head.

Multiple drills differ from milling machines and lathes, in that the latter are built alike or are what are termed stock machines. Multiple drills, however, have to be put up to suit many different customers, and to accord with the requirements of different drilling layouts, and while it is true that drill heads of a given size will perform work with variations within a certain range, yet to meet all requirements, different sizes of drilling heads must be employed and also different layouts of the drilling spindles must be used in each of the different sized heads. It is, therefore, of importance to build the multiple drilling machine as fully as possible like a stock machine, and in carrying out this purpose in connection with the present invention, the machine is built as a stock organization up to and including the saddle, so that this saddle with the column and the parts carried thereby may be a stock organization, ready to have assembled therewith heads of different sizes, or heads having different drill layouts.

The shaft c^3 of the shrouded pinion is driven through connections from a vertical shaft D' , having on its lower end a worm 41 meshing with a worm wheel 40. The worm wheel 40 is fixed on a shaft 42 mounted in a clutch box 43, carried by the head C or saddle. This shaft has mounted thereon a clutch C^3 which is slid along the shaft by fingers 44 pivoted to a collar 44'. To overcome the end thrust this collar is adjustably secured to the shaft by a screw thread. The fingers are operated by a cam collar 45 loose on the shaft. This collar is operated by a fork 46 on the shaft 26 which is operated by a hand lever 23. The clutch C^3 , when set, turns the pinion 47, which through reduction gearing 48, 49, 50 operates the shaft c^3 of the rack pinion C^2 .

The worm 41 is splined to the shaft D' and as the saddle together with the head moves up and down, due to the shrouded pinion traversing the rack B' , the said worm 41 will move up and down along the shaft D' , and the entire clutch or worm gear box 43 partakes of this up and down movement with the saddle and head.

At the top of the column B is located variable speed feed gearing for the shaft D' , this gearing being located in casing D, suitably secured to the column. This variable speed feeding gearing is driven from a pulley E which drives the shaft G. The shaft G carries a group of three gears d , shifted along the shaft by a lever 61^a. This lever is mounted on a vertical shaft 61 which extends down to a control lever 61''. The gears d are adapted to separately engage the gears d' , d^2 , d^3 on a sleeve d^4 held on shaft

R mounted in suitable bearings in the housing D of this speed gear mechanism. The shaft can be removed without removing the sleeve. By shifting the set d of three gears, three different speed changes can be secured through the gears d' , d^2 and d^3 respectively. The gear d^3 transmits the motion in either case to a shaft 54, carrying a gear 55, meshing with the gear d^3 , and this shaft has a two-speed gear 56, having a grooved portion adapted to connect with a lever 62 mounted in a bearing 62' and operated by a handle 62''.

The two-speed change feed gear 56 is adapted to engage respectively with gears 57', 57'' on a shaft 57, which carries fixed thereto the gears just mentioned, and also gears 57^a and 57^b. These gears are adapted to mesh with gears of a shifting group 58, splined to a shaft 59, shiftable to get the desired gear engagement by a lever 63 operated by a handle 63'.

In Fig. 6 this gearing is shown developed or spread out for convenience of illustration and understanding.

The shaft 59 carries a worm 60 meshing with a worm wheel 51 on a shaft section D^2 . This shaft section has its bearings in the housing of the variable speed gear mechanism, and it is connected with a stub shaft D'' by a compensating coupling which we term a floating shaft coupling. Stub shaft D'' is connected with feed shaft D' by a collar D^5 fastened by taper pins. This enables the shaft D' to be removed and replaced at will, without disturbing the stub shaft D'' , which remains mounted in its housing. The feed shaft D' , by reason of its splined or key way connection with the worm 41, can be dropped down through this worm and removed from the machine after having first detached it from the stub shaft D'' by unfastening the collar D^5 . This action can be carried out without disturbing the feed gear box or any of the feed gearing connections at the top of the machine. This floating coupling comprises a member D^3 on the short shaft section D^2 and a member D^4 on the upper end of the shaft D'' . These two members are connected by a central member or plate 65, which has tongue and groove connections 66 and 66' with the parts D^3 and D^4 respectively, these tongues extending at right angles to each other. This floating coupling compensates for any offset relation of the shaft members D^2 and D'' .

The advantage of this connection is that it renders it possible to jig-drill the feed works into the casing or head and assemble the head on the column and connect the vertical shaft D' to the feed gear mechanism even though the feed shaft D' does not perfectly line up with the said feed gear mechanism. The shaft D' , as above described, is connected at its lower end through the worm and

worm gear, and thence through the clutch C³ with the shaft of the shrouded pinion and the clutch serves the purpose of connecting or disconnecting the shrouded pinion shaft 5 from the vertical drive shaft D', and hence this vertical drive shaft does not require, as is the case with other forms of construction, to be shifted laterally to engage or disengage the worm with the worm gear. But in order 10 to line up the shaft with the feed gear mechanism at the top it would be necessary, were the floating coupling D³, D⁴ not employed, to assemble the feed gear mechanism on the column and bore the connecting holes in the 15 head after the machine is assembled. This requires exceptionally accurate work which is avoided by our construction, in which we employ the floating coupling between the vertical shaft D' and the shaft section D².

20 The gearing in the gear chest C' is driven from a vertical shaft O, which in turn is driven through bevelled gearing from the shaft R, above described.

We have also provided means whereby the 25 same head or gear chest C' which is employed for a double speed spindle organization, can be used in a single speed spindle form of machine. This improvement comprises a filling-in plate 70, Fig. 16, which 30 is supported on the base plate 72 of the gear chest or head C' when this chest is used in a single speed spindle machine. The plate has ball bearings 73 for the hollow shaft 74 of the gears 4, and it also has openings to 35 receive the bushings 77 which afford bearings for the spindles 3 of the pinions 5, it being understood that the spindles 3 are connected with the drill spindles C' by flexible couplings. The single speed spindle arrangement is designed for doing heavier 40 work than a two-speed spindle arrangement, and hence the same light casting or head and gear chest can be adapted for the heavier work of the single speed spindle arrangement by applying the reenforcing or filling-in plate 70 with its additional bearing facilities afforded by the longer bushings 77, which are backed not only by the frame of the chest, in this particular instance by base 45 plate 72, but also by the filling-in plate.

With the single speed spindle organization the pinion 5 is formed integral with the spindle for doing heavy work.

In addition to this filling-in plate there 55 is provided in this single speed spindle organization a cover plate 75' which is supported on the upstanding flange 70' of the filling-in plate. This cover plate affords an upper bearing for the top of the spindle, and 60 this bearing is provided with a bushing 75'.

An advantage gained by this construction is that in case it is desired to have in one drilling circle spindles running at different speeds, this can be accomplished by extending, say every other spindle above the top 65

or cover plate 75', as shown in Fig. 16, the pinion 5 being omitted, and affixing thereto a pinion 5' of larger diameter than the pinion 5, and have this mesh with a smaller gear 4' than the gear 4.

This would cause alternate drills to run at a slower speed than the other drills in the same circle.

When the gear chest is to be used in a two-speed spindle machine, the reenforcing or filling-in plate is not used, see Fig. 17. It will thus be seen that we have provided a gear chest or head which may be used interchangeably in either a single or a double speed spindle machine, said head when used 75 in a single speed spindle machine having the filling-in plate attached thereto and when used in a two-speed spindle machine being 80 without this plate.

In the double speed spindle machine a lifting fork 93 is employed to shift a double pinion 5' vertically, as shown in Fig. 17, to change the speed, and the omission of the filling-in plate in the two-speed spindle head affords the room for the working of 85 this lifting fork, or, to put the matter in another way, as the lifting fork is not employed in the single speed spindle machine, there is space for the use of the filling-in plate 70 to give the additional bearing facilities and strength desirable in a single speed spindle machine for doing heavier work or installing a larger number of spindles than 90 with a double-speed spindle machine.

In order to adjust the pinions of the two 100 pinion gear chest, we provide a fulcrum post 103 mounted on the casing C', which carries the detent 105, which engages the grooves in the vertically adjustable rod 106 connected with the lifting fork 93 of the double pinion. The post 103 is provided with a plurality of 105 grooves to receive the fork 107 of the lifting lever. By this fulcrum post the shifting fork can be moved either up or down by a 110 leverage action.

We have also improved the bearing for the main driving shaft O of the gear chest. This bearing includes a thrust ball bearing 80, which takes the pull of the shaft in drilling, and the other ball bearing 81 which takes the lateral strain. The construction involves a ring 82, having a flange 82', resting on the upper surface of the gear chest, said ring having a lip 83 for holding the members of the lower ball bearing 81 in 115 place. This lip holds the race ring, and the ball bearing 80 comprise an upper and a lower race ring, the latter resting on the race rings of the lower ball bearing. The bearing is completed by a cap member 84 which is held in place by bolts, and by removing these the entire bearing may be 120 removed.

The drill head with its saddle and the clutch and worm gear box are counterbal- 125 130

anced by weights 85 arranged within the column and connected with the head by chains or other flexible connections 86 extending over pulleys 87.

- 5 Reverting to the variable feeding gear works at the top of the column in its relation to and cooperation with the two vertical shafts D' and O, the former giving variable vertical movement to the saddle with
 10 the drilling head, and the latter giving varying speeds to the drills through the gearing in the gear chest, it will be observed that vertical shaft O is variably driven by shifting the group of gears d of the main
 15 drive shaft G, to engage either one of the gears d', d² or d³ of the shaft R. It will be observed further, that the gear d³, forming a part of this variable speed drive for the vertical shaft O of the spindle organization,
 20 forms a part of the gear train leading to the vertical feed shaft D'. That is to say, this gear d³ communicates its power and its varying speed through the gearing on shafts 54, 57 and 59, and the speed of the shaft 59
 25 is varied by the shifting of the groups of gears on said shaft 59 and on the shaft 54.

We have provided means for taking care of oil discharged from the bearings of the spindles 3 of the pinions of the gear chest.

- 30 This means consists of disks 90 as shown in Fig. 19, arranged below the gear chest and at the lower ends of the bushings 77. These disks have their edges located at some distance from the center of rotation and they overlap a pan or tray 91 which is adapted to catch the oil thrown off from these disks. This oil is conveyed back to a suitable source by the pipe 92. This disk can be flanged up
 35 where it engages the shaft and flanged down at its periphery.

Reverting to the vertical shaft D' which carries the worm for driving the shrouded pinion through certain intermediate connections, it will be observed that this shaft has
 40 no lateral movement to control the operation of this power transmitting connection, and hence this whole mechanism can be housed and the housing supplied with lubricant to lubricate all of the parts therein.

- 45 50 We have provided special means for holding the arms 95 Fig. 19, which act as holders for the lower sections c' of the flexible shafts which carry the drilling tools. This means consists of a bolt 97, a cup washer 98, a light washer 99, a spring 100, and a nut 101. When the nut 101 is released, if no provision were made to prevent it, the arm would tip forward and make it difficult to locate the drill in the proper position.

- 55 60 To avoid this, the spring 100 is employed in the cup washer so that when the nut 101 is slacked off to make an opening at 102, which is done in order to adjust the arm, the spring will still hold the arm up against the underside of the head, but will admit of the

arm being adjusted. After the proper adjustment of the arm is made, the nut 101 is tightened up, making a solid clamping connection.

In Fig. 5 we show a pivoted safety catch 70 108 which, if the chain or flexible connection 86 breaks, will be drawn down by spring 109 to make its teeth 110 engage with the rack B' and hold the head against falling down.

Reverting to the gearing at the top of the column, the drive shaft G and the speed shaft R are mounted in the main gear casing D. This has an open side to which is removably attached the supplemental gear casing D^x in which are mounted the shafts, 80 54, 57, 59 and the variable feed gearing for driving the feed shaft D'. This supplemental casing or gear box has attached thereto the auxiliary housing D⁶ in which the stub shaft D'' bears. It also carries a bearing 61^b in which the stub shaft 61^c is mounted. This stub shaft carries the arm 61^a for shifting the speed changing gears on the drive shaft G of the main gear box D. This stub shaft is connected to the shaft 61 90 by a detachable coupling 61^d.

By reason of the fact that the supplemental gear casing D^x can be adjusted up or down or towards the front or back of the machine, the assembly of the parts at the 95 head of the machine is facilitated, making for economy of time and accuracy of adjustment. It can be quickly located centrally of the opening in the main gear box, and being formed separately from the main gear 100 casing D, it can be moved readily, and can be jig drilled independently. It with its feed gearing can be removed without disturbing the main casing with its speed gearing.

From the above description it will be seen that the feed gearing is driven from one of the gears on the speed shaft R. The feed gearing in the supplemental gear box rotates at high speed, which speed is variable, and the main reduction of the speed is made in the train of connection at a point between this variable speed feed gearing and the shrouded pinion shaft.

The adjusting handles 62'', 63' for the feed gearing, and the adjusting means for the speed gearing (of the main casing), viz., the arm 61 and stub shaft 61^c, are all mounted on and removable as one body with the supplemental gear casing.

A stopping lever is shown at L. This controls a suitable clutch at pulley E, through lever K, shaft J, arm I, and rod H.

Having thus described our invention, what we claim is:—

1. In combination in a drilling machine, a single column, a saddle slidable vertically of and wholly supported by said single column on the face thereof, a drill carrying head projecting from the said saddle and 120

detachably connected therewith for replacement by another head having a different drill layout, said saddle projecting below the lower face of the drill head, and means for 5 making the saddle traverse the column, substantially as described.

2. In combination in a drilling machine, a single column, a saddle slidable vertically of and wholly supported by said single 10 column on the face thereof, a drill carrying head projecting from the said saddle and detachably connected therewith for replacement by another head having a different drill layout, said saddle projecting below 15 the lower face of the drill head, means for making the saddle traverse the column, said means consisting of feed works carried by the saddle and including a pinion and a rack on the column with which said pinion 20 engages, substantially as described.

3. In combination in a drilling machine, a single column, a saddle slidably mounted on the front face of the column and having a channel in its rear face, a central opening 25 and bearings on opposite sides of the central opening, a vertical rack on the front face of the column and in the channel in the rear face of the saddle, a shaft mounted in the bearings of the saddle and having 30 teeth therein to form a pinion registering with the central opening and engaging the rack, substantially as described.

4. In combination in a drilling machine, a column, a head carrying the drills, a shaft 35 extending to the head for driving the drills, a saddle slidable vertically on the column and to which the head is connected, a rack on the column, a pinion carried by the saddle, a vertical shaft extending along the 40 column, power transmitting means between the lower end of said shaft and the pinion shaft, said vertical shaft being supported in bearings both its upper and lower ends maintaining it against lateral movement, 45 gearing at the top of the column for driving said vertical shaft, a floating coupling at the upper end of the vertical shaft to transmit power thereto from the said gearing, a horizontal drive shaft for said gearing, a horizontal shaft geared to the shaft 50 which drives the drills, and gearing for driving the latter horizontal shaft from the drive shaft, substantially as described.

5. In combination in a drilling machine, 55 a column, a head carrying the drills, a shaft extending to the head for driving the drills, a saddle, slidable vertically on the column and to which the head is connected, a rack on the column, a pinion carried by 60 the saddle together with its horizontal shaft, a vertical feed shaft, power transmitting means between the lower end of said shaft and the pinion shaft, said vertical feed shaft being supported in bearings at both its upper 65 and lower ends, maintaining it against lat-

eral movement, gearing at the top of the column for driving said vertical feed shaft, a floating coupling at the upper end of the vertical feed shaft to transmit power thereto from the said gearing, and a vertical shaft 70 section, driven by said gearing, said shaft section and vertical feed shaft first mentioned being parallel and having the parts of the floating coupling connected thereto.

6. In combination in a drilling machine, 75 a column, having a vertical rack, a drill head, a pinion engaging the rack for moving the drill head along the column, feed gear works at the top of the column for driving the pinion, and a vertical feed shaft held 80 at its upper and lower ends against lateral play, a vertical shaft section above the vertical feed shaft, driven by the feed gear works, and a floating coupling between the said vertical shaft section and vertical feed 85 shaft section, substantially as described.

7. In combination, in a drilling machine, a column, a drill head saddle slidable vertically thereon, a drill head and gear chest carried thereby, a rack on the column, a 90 pinion, a shaft carrying the pinion and mounted on the saddle, a vertical shaft, geared to the pinion shaft for driving it, gearing in the chest of the head for driving the drill spindles, a vertical shaft for driving 95 said gearing in said chest, a variable speed gear works for driving the two vertical shafts, comprising a main drive shaft arranged horizontally, a shaft parallel therewith geared to the vertical shaft of the gear chest, shifting variable speed gears on the drive shaft, complementary gears on the said parallel shaft, a plurality of other shafts parallel with the shaft first mentioned, the first of said shafts being geared 100 to one of the gears of the parallel shaft first mentioned and the final one of said other parallel shafts being geared to the vertical feed shaft of the saddle, and variable speed gearing between said other parallel shafts, 105 substantially as described.

8. In combination, a column, a drill head slidably connected therewith, drills carried thereby, a gear box, a pair of shafts extending down from the gear box, one of said 110 shafts being for driving the drills and the other for imparting sliding movement to the drill head, gearing between the lower ends of said shafts and the drills and head respectively, gearing in the gear box for 115 driving said shafts, said gearing including a plurality of gears, a sleeve carrying the same, and a shaft passing through the sleeve bearing in the gear box and connected with the sleeve, said shaft being removable from 120 the sleeve and gear box, and means for retaining the sleeve in normal position in the gear box when said shaft is removed, substantially as described.

9. In a drill a gear chest, vertical shafts 125

therein, gears on said shafts, spindles carrying pinions meshing with the gears for driving the drills, and a removable insert plate at the lower part of the gear chest having bearings for the pinion spindles, said plate by its removal providing space adapting the gear chest to a two speed gear set, substantially as described.

10. In a drill a gear chest, vertical shafts therein, gears on said shafts, spindles carrying pinions meshing with the gears for driving the drills, a removable insert plate at the lower part of the gear chest having bearings for the spindles, and a second insert plate above the pinions in the gear chest also having bearings for the said spindles.

11. In a drill a gear chest, vertical shafts therein, gears on said shafts, an upper insert plate in the chest affording bearings for the shafts, spindles carrying pinions meshing with the gears for driving the drills, and a removable insert plate at the lower part of the gear chest having bearings for the pinion spindles, said plate by its removal providing space adapting the gear chest to a two speed gear set, said upper insert plate being supported on the lower by a flange on one bearing on the other.

12. In combination in a drilling machine, a gear chest having gears for driving the drill spindles, shiftable pinions for varying the speed of the spindles, grooved rods for adjusting the pinions extending above the chest, and means on the top of the gear chest to serve as a fulcrum for a lever for operating the rod, substantially as described.

13. In combination in a drilling machine, a gear chest having gears for driving the drill spindles, shiftable pinions for varying the speed of the spindles, grooved rods for adjusting the pinions, and posts on the gear chest to serve as a fulcrum for a lever for operating the rod, said post having a plurality of fulcrum bearings for the operating lever, substantially as described.

14. In a drilling machine, a gear chest, gears therein, spindles driving from said gears, a shaft extending into the top of the gear chest substantially centrally thereof, a master gear on said shaft for driving the gears in said chest and a bearing for said shaft comprising a ring, secured to the gear chest, two ball bearings carried by the ring, one above the other, one for sustaining the lateral thrust and the other the longitudinal thrust, and a cap member for said ring, the ball bearing race rings being held between said cap and a lip on the lower part of the said ring, substantially as described.

15. In combination, a column, a head movable along the column, spindles carried by the head, means for driving the spindles, means for moving the head along the column, including a pinion and a rack, the latter being on the column, a counter weight

for the head, a flexible connection between the same and the head, a pulley for guiding said connection, and a safety catch under spring tension to which the end of the flexible connection is joined to exert its lifting force through said catch, said catch when the connection breaks engaging the rack under force of the spring, said catch being pivotally mounted and with the spring acting in opposition to the pull of the flexible connection, substantially as described.

16. In combination in a drilling machine, a series of drill spindles, a gear chest having gearing for operating the said spindles, an insert plate at the lower part of the gear chest, pinions on certain of the spindles above the said insert plate, a second insert plate located in a plane above the pinions, and pinions above said second insert plate for driving certain of the spindles, substantially as described.

17. In combination in a drilling machine, a column, a tool carrying member mounted to slide on the column, and having an opening at a point intermediate of its width with a shaft bearing at each side thereof, a rack on the column, and a removable shaft mounted in the said bearing of said tool carrying member, said removable shaft having teeth therein providing a pinion of no greater diameter than the adjacent part of the shaft and thus adapted to slip through one of the bearings, said pinion engaging the rack through the said opening, substantially as described.

18. In combination in a drilling machine, a column, a gear box at the upper end thereof, a tool carrier slidably mounted on the column, a rack on the column, a pinion mounted in the tool carrier, a vertical shaft, power transmitting means between the lower end of said shaft and the pinion shaft, bearings for said shaft maintaining it against lateral movement, a stub shaft in the gear box parallel with the vertical shaft, gearing in the gear box at the top of the column for driving said stub shaft, and a floating coupling at the upper end of the vertical shaft to transmit power thereto from said parallel stub shaft, substantially as described.

19. In combination in a drilling machine, a column, a tool carrier slidable thereon, a vertical shaft at the side of the column having connections for moving the said tool carrier, variable speed gearing at the top of the column for driving said shaft, an arm for adjusting said gearing to change the speed, a vertical shaft carrying said arm at its upper end and extending down along side the column, and a hand lever located on the side of the column for operating the said shaft, substantially as described.

20. In combination in a drilling machine, a column, a tool carrier slidable thereon, a

- vertical shaft with driving connections to the tool carrier to feed it along the column, change speed gearing at the top of the column, a casing therefor, a removable supplemental casing, gearing therein for communicating motion from the speed gearing to said vertical shaft, a vertical stub shaft mounted in the supplemental casing, and having means for setting the speed gearing, 5 a shaft extending alongside the column, a detachable connection between said shaft and the stub shaft, and a handle for operating the vertical shaft, substantially as described.
- 10 21. In combination in a drilling machine, a column, a drill head slidable vertically thereof, a rack on the column, a pinion on the drill head, a vertical feed shaft extending alongside the column, gearing for driving the pinion from said vertical shaft, a vertical tool driving shaft geared to the drills, a horizontal speed shaft geared to the vertical tool driving shaft, a main gear box supported on the column and in which said 15 horizontal shaft bears, a drive shaft also mounted in the main gear box and having a variable gear connection between it and the speed shaft, a supplemental casing detachably secured to the main casing, a vertical stub shaft mounted in the supplemental casing, a floating coupling between said stub shaft and the vertical feed shaft, variable speed gearing between the speed shaft and the vertical stub shaft including shiftable 20 gears, and handles mounted on the supplemental casing and connected with the shifting gears, substantially as described.
- 25 22. In combination, a column, a tool carrier slidable thereon, a vertical feed shaft for the carrier, having connections for driving said carrier, a main gear casing at the top of the column, a driving shaft and a speed shaft mounted horizontally therein, a supplemental casing detachably secured to the 30 side of the main gear casing, variable feed gearing in said supplemental casing, hand operable means on the supplemental casing for setting the feed gearing, variable speed gearing between the drive shaft and the speed shaft, and means mounted in the supplemental casing for setting the speed gearing, said feed gearing being driven from one of the gears on the speed shaft, substantially as described.
- 35 23. In combination in a machine of the class described, a column, a tool carrying head movable along the same, a vertical feed shaft, driving connections between the same and the head for moving the latter on the 40 column, a feed gear box at the top of the 45
- column, a stub shaft driven from the gearing within the column, and a detachable coupling between the stub shaft and the feed shaft, substantially as described.
- 50 24. In combination in a machine of the character described, a column, a tool carrying head movable along the same, a vertical feed shaft with driving connections between the same and the head for moving the latter along the column, a feed gear box at the 55 top of the column, a vertical shaft section driven by the feed gearing, a stub shaft, a floating coupling between the vertical shaft section and the stub shaft, to compensate for disalignment of said shafts, and a detachable coupling between the feed shaft and the stub shaft, substantially as described.
- 60 25. In combination, a column, a tool carrying head slidably mounted thereon, a vertical feed shaft, driving connections between the feed shaft and the head, including a gear having a key and key way connection with the vertical feed shaft, said key way extending along the feed shaft to its upper end, driving means for the feed shaft at the upper end thereof, and a detachable connection between the driving means and the vertical feed shaft, whereby the latter may be dropped down through the gear and removed from the machine without disturbing either the driving means for the vertical feed shaft or the driving connections leading therefrom, substantially as described.
- 65 26. In combination in a drilling machine, a single column, a drill carrying head slidable vertically of said column, and projecting from the face of said column, a rack on the column and a horizontal pinion shaft supported in bearings connected with the head, a gear box at the top of the column, a vertical shaft extending alongside the column and driven from gearing in the gear box, driving connections between the lower end of the said vertical shaft and the horizontal pinion shaft, a shaft driven by the gears in the gear box and extending forwardly from said box over the projecting drill carrying head, and a vertical shaft 70 driven from the horizontal shaft and extending down to the drill head to drive the drills.
- 75 27. In testimony whereof we affix our signatures.
